COMPOSITIONS CONTAINING PYRAZOLYLPYRIDINIUM SALTS AND METHOD OF ADMINISTRATION

Edward Charles Tocus, West Nyack, N.Y., and Victor John Bauer, Montvale, N.J., assignors to American Cyanamid Company, Stamford, Conn., a corporation of Maine

No Drawing. Filed June 15, 1965, Ser. No. 464,192
20 Claims. (Cl. 167—65)

This invention relates to new compositions of matter. More particularly, it relates to compositions containing as an active ingredient a pyrazolylpyridinium salt and method of administering the same.

The active components of the new compositions may be illustrated by the following formula:

wherein R is selected from the group consisting of hydrogen, lower alkyl and cyclopropyl; R₁ is selected from the group consisting of hydrogen and lower alkyl; R₂ is selected from the group consisting of lower alkyl, lower alkenyl, cinnamyl, cyclopropyl-methyl and lower alkoxy(lower)alkyl; R₃ is selected from the group consisting of hydrogen and lower alkyl and X is a pharmaceutically acceptable anion such as, for example, chloride, bromide or iodide. Illustrations of compounds of the present compositions and their activity are shown in table herein-after.

The above-described compounds which are active components of the compositions of this invention may be prepared by a three-stage sequence. Thus, an ester of a pyridine-4-carboxylic acid is reacted with a methyl ketone to provide a 1-(4-pyridyl)-1,3-alkyldione; or ethyl formate is reacted with a pyridyl ketone in the presence of a base such as, for example, sodium methoxide to provide a 1-(4-pyridyl)-1,3-alkyldione salt. The resulting dione or salt is reacted with hydrazine hydrate or hydrazine dihydrochloride to give a 4-[3(5)-pyrazolyl]pyridine. These latter compounds are quaternized to the active components of this invention generically described as 4-[3(5)-pyrazolyl]-pyridinium salts, with a lower alkyl, lower alkenyl, cinnamyl, cyclopropylmethyl, or lower alkoxy(lower)alkyl halide. These reactions can be illustrated schematically as follows:

2

wherein R, R₁, R₂, R₃ and X are as hereinbefore defined and A is a lower alkyl group. The preparation of the active ingredients of the compositions of this invention will be described in greater detail in conjunction with the examples hereinafter.

The active components of the compositions of this invention have been found, in standard laboratory measurements using chicks and alloxan-diabetic mice, to be orally active hypoglycemic agents. The procedure used to measure blood sugar-lowering properties of the active ingredients of the compositions of this invention are as follows:

(A) Not less than two Hall Cross cockerels, 18–20 days 30 of age, weighing 120–200 grams are fasted 18 hours before oral administration of each test compound. For administration the test compound is suspended in 0.5% aqueous carboxymethylcellulose solution such that one milliliter of suspension per 100 grams of chick contains the intended dose. Two hours after drug administration, blood samples are obtained from the wing veins and analyzed for blood glucose concentrations by means of a Technicon Auto Analyzer using the method of W. S. Hoffman, J. Biol. Chem. 120, 51 (1937). Appropriate 35 standards and controls are tested at the same time for comparison. An average reduction of blood glucose concentration greater than 12% is considered hypoglycemic.

(B) Alloxan monohydrate causes selective destruction of the insulin producing β -cells of the pancreas with 45 consequent diabetes in experimental animals. Manor Farms male mice weighing 23–27 grams are given intravenously 80 mg./kg. of aqueous alloxan monohydrate via the tail vein five days before oral administration of the test compound. The test compound is suspended in 50 0.5% aqueous carboxymethyl-cellulose solution such that 0.2 milliliter of suspension per 25 grams of mouse contains the intended dose. Groups of not less than 5 mice for each dose are bled from the tail immediately prior to, and 2 to 4 hours after, oral administration of the test compound. Blood is analyzed for glucose concentrations as described for chicks. Appropriate controls and standards are tested at the same time for comparison.

Results obtained from the administration of active components of the compositions of this invention compared to standard commercial anti-diabetic agents are shown in the table.

In general, the active ingredients of the compositions of this invention are given at doses from 1 to 250 mg. per kilogram body weight of warm-blooded animal. 65 The following table summarizes results obtained when the active components of the present compositions are tested as described above.

The amount of active ingredient to be given will depend upon the age, condition, weight and other factors present in the warm-blooded animal. In the instance of a warm-blooded animal of, for example, 75 kg. the dose may vary from 0.075 g. to 18.75 g.

5 boxymethylcellulose, methylcellulose, polyvinylpyrrolidone, gelatin and the like. Sterile suspensions or solutions are required where parenteral use is desired. Isotonic preparations containing suitable preservatives are also highly desirable for injection use.

The active components of this invention can be used in the form of compositions preferably for oral administration in unit dosage form such as tablets, pills, capsules, powders, granules or oral solutions or suspensions and the like. They may also be used as sterile parenteral solutions or suspensions. For preparing solid compositions such as tablets, the principal active ingredient is mixed with conventional tableting ingredients such as corn starch, lactose, sucrose, sorbitol, talc, stearic acid, magnesium stearate, dicalcium phosphate, gums, and fractionally similar materials as pharmaceutical diluents or carriers. The tablets or pills of the novel compositions can be laminated or otherwise compounded to provide a dosage form affording the advantage of prolonged or delayed action or predetermined successive action of the enclosed medication. For example, the tablet or pill can comprise an inner dosage and an outer dosage component, the latter being in the form of an envelopé over the former. The two components can be separated by an enteric layer which serves to resist disintegration in the stomach and permits the inner component to pass intact into the duodenum or to be delayed in release. A variety of materials can be used for such enteric layers or coatings, such materials including a number of polymeric acids or mixtures of polymeric acids with such materials as shellac, shellac and cetyl alcohol, cellulose acetate and the like. A particularly advantageous enteric coating comprises a styrene maleic acid copolymer together with known materials contributing to the enteric properties of the coating.

The liquid forms in which the novel composition of the present invention may be incorporated for administration include aqueous solutions, suitably flavored emulsions with edible oils, such as, cottonseed oil, sesame oil, coconut oil, peanut oil and the like, as well as elixirs and similar vehicles well known in the pharmaceutical compounding arts. Suitable dispersing or suspending agents for aqueous suspensions include synthetic and natural gums, such as, tragacanth, acacia, alginate, dextran, sodium car-

55 The term unit dosage form as used in the specification and/or claims refers to physically discrete units suitable as unitary dosage for warm-blooded animal subjects, each unit containing a predetermined quantity of active material calculated to produce the desired therapeutic effect in association with the required pharmaceutical diluent, carrier or vehicle. The specifications for the novel unit dosage forms of this invention are dictated by and are directly dependent on (a) the unique characteristics of the active material and the amount of blood sugar-lowering effect to be achieved, and (b) the limitations inherent in the art of compounding such an active material for therapeutic use in warm-blooded animals as disclosed in detail in this specification, these being features of the present invention. Examples of suitable oral unit dosage forms in accord with this invention are tablets, capsules, pills, powder packets, granules, wafers, cachets, teaspoonsfuls, dropperfuls, ampules, vials, segregated multiples of any of the foregoing, and other forms as herein described.

55 The present invention will be described in greater detail in the examples which follow which describe the preparation of 4-[3(5)-pyrazolyl]pyridinium salts and formulations containing the active components.

EXAMPLE 1

Preparation of 1-(4-pyridyl)-1,3-pentanedione

A mixture of 137 g. (1 mole) of methyl isonicotinate, 65 200 ml. of methyl ethyl ketone, 1 l. of ether, and 59.4 g. (1.1 moles) of sodium methoxide is heated under reflux with stirring on a steam bath for 3 hours. The mixture is cooled, acidified with 100 ml. of acetic acid, and diluted with 500 ml. of water. The ether layer is separated, and 70 the aqueous phase extracted with ether. The combined ether solution is dried over anhydrous magnesium sulfate, and concentrated under reduced pressure to 137 g. of red liquid

$\lambda_{\text{max}}^{\text{MeOH}}$ 308 m μ .

5

The liquid gives a deep red color with ferric chloride test solution.

EXAMPLE 2

Preparation of 5-methyl-1-(4-pyridyl)-1,3-hexanedione

The above compound is obtained as a red liquid from the reaction between methyl isobutyl ketone and methyl isonicotinate under the conditions described in Example 1.

EXAMPLE 3

Preparation of 1-cyclopropyl-3-(4-pyridyl)-1,3-propanedione

This compound is obtained as a red liquid from the reaction between methyl cyclopropyl ketone and methyl isonicotinate under the conditions described in Example 1.

EXAMPLE 4

Preparation of 1-(3-methyl-4-pyridyl)-1,3-butanedione

The above compound is obtained as a red liquid from the reaction of acetone and methyl 3-methylisonicotinate under the conditions described in Example 1.

EXAMPLE 5

Preparation of 1-(4-pyridyl)-1,3-propanedione sodium salt

A mixture of 74 g. (1 mole) of ethyl formate, 60.5 g. (0.5 mole) of methyl 4-pyridyl ketone, 54 g. (1 mole) of sodium methoxide, and 900 ml. of benzene is heated under reflux on a steam bath with stirring for 18 hours. The mixture is cooled and filtered. The solid is washed with benzene and cold methanol, and dried, leaving 65 g. of a light brown solid, the sodium salt of the dione.

EXAMPLE 6

Preparation of 2-methyl-1-(4-pyridyl)-1,3-propanedione sodium salt

The above compound is obtained as a brown solid from the reaction of ethyl formate and ethyl 4-pyridyl ketone under the conditions described in Example 5.

EXAMPLE 7

Preparation of 4-[5(3)-ethyl-3(5)-pyrazolyl]pyridine

To a stirred solution of 300 g. of 100% hydrazine hydrate is added during 15 minutes 137 g. (0.77 mole) of crude 1-(4-pyridyl)-1,3-pentanedione. The temperature of the solution rises to 85° C. The mixture is stirred at room temperature for 1 hour, diluted with 450 ml. of water, and stored overnight at 5° C. The solid which separates is collected and dried, and it is twice recrystallized from acetone. The product weighs 31 g. and is white crystals, melting point 116°-117° C.

EXAMPLE 8

Preparation of 4-[5(3)-isobutyl-3(5)-pyrazolyl]pyridine

The compound, colorless crystals, melting point 156°-157° C., is prepared from hydrazine hydrate and 5-methyl-1-(4-pyridyl)-1,3-hexanedione under the conditions described in Example 7.

EXAMPLE 9

Preparation of 4-[5(3)-cyclopropyl-3(5)-pyrazolyl]pyridine

The above compound, colorless crystals, melting point 126°-127° C. is prepared from hydrazine hydrate and 1-cyclopropyl-3-(4-pyridyl)-1,3-propanedione under the conditions as described in Example 7.

EXAMPLE 10

Preparation of 3-methyl-4-[5(3)-methyl-3(5)-pyrazolyl]pyridine

This compound, light brown crystals, melting point 136°-138° C., is prepared from hydrazine hydrate and

6

1-(3-methyl-4-pyridyl)-1,3-butanedione in the manner described in Example 7.

EXAMPLE 11

Preparation of 4[3(5)-pyrazolyl]pyridine

To a stirred solution of 7.5 g. (0.07 mole) of hydrazine dihydrochloride in 50 ml. of water is added 5.0 g. (0.034 mole) of 1-(4-pyridyl)-1,3-propanedione sodium salt. After 2 hours, the solution is neutralized with sodium hydroxide, and the solid which separates is collected. Three recrystallizations from acetone give a colorless solid, melting point 154°-155° C.

EXAMPLE 12

Preparation of 4-[4-methyl-3(5)-pyrazolyl]pyridine

The above compound, a viscous orange liquid,

$\lambda_{\text{max}}^{\text{MeOH}}$ 260 m μ

is prepared from the reaction of hydrazine dihydrochloride and 2-methyl-1-(4-pyridyl)-1,3-propanedione sodium salt following the conditions as described in Example 11.

EXAMPLE 13

Preparation of 1-methyl-4-[5(3)-ethyl-3(5)-pyrazolyl]pyridinium iodide

A mixture of 17.3 g. (0.1 mole) of 4-[5(3)-ethyl-3(5)-pyrazolyl]pyridine, 43 g. (0.3 mole) of methyl iodide, and 800 ml. of ether is stirred for 5 hours, and allowed to stand overnight at room temperature. A tan solid, 31 g., melting point 209°-211° C. is collected. Two recrystallizations from methanol provide 17 g. of colorless crystals, melting point 213°-214° C.

$\lambda_{\text{max}}^{\text{MeOH}}$ 304 m μ

EXAMPLE 14

Preparation of 1-methyl-4-[5(3)-methyl-3(5)-pyrazolyl]pyridinium iodide

The compound, off-white crystals, melting point 251°-252° C., is prepared from 4-[5(3)-methyl-3(5)-pyrazolyl]pyridine and methyl iodide as described in Example 13.

EXAMPLE 15

Preparation of 1-ethyl-4-[5(3)-methyl-3(5)-pyrazolyl]pyridinium iodide

The above compound, colorless crystals, melting point 175°-176° C., is prepared from 4-[5(3)-methyl-3(5)-pyrazolyl]pyridine and ethyl iodide following the procedure of Example 13, except that the reaction is carried out for 2 hours under reflux in ethanol.

EXAMPLE 16

Preparation of 1-n-butyl-4-[5(3)-methyl-3(5)-pyrazolyl]pyridinium bromide

The compound, colorless crystals, melting point 211°-212° C., is prepared from 4-[5(3)-methyl-3(5)-pyrazolyl]pyridine and n-butyl bromide as described in Example 13, except that the reaction is carried out for 18 hours under reflux in n-butyl alcohol.

EXAMPLE 17

Preparation of 1-methyl-4-[3(5)-pyrazolyl]pyridinium iodide

The compound, colorless crystals, melting point 189°-190° C., is prepared from 4-[3(5)-pyrazolyl]pyridine and methyl iodide as described in Example 13, except that the reaction is carried out for 18 hours at room temperature in methanol.

EXAMPLE 18

Preparation of 1-n-propyl-4-[5(3)-methyl-3(5)-pyrazolyl]pyridinium bromide

The above compound, colorless crystals, melting point 247°–248° C., is prepared using 4-[5(3)-methyl-3(5)-pyrazolyl]pyridine and n-propyl bromide in the procedure in Example 13, except that the reaction is carried out for 18 hours under reflux in ethanol.

EXAMPLE 19

Preparation of 1-methyl-4-[5(3)-isobutyl-3(5)-pyrazolyl]pyridinium iodide

The compound, colorless crystals, melting point 206°–207° C., is prepared from 4-[5(3)-isobutyl-3(5)-pyrazolyl]pyridine and methyl iodide as described in Example 13.

EXAMPLE 20

Preparation of 1-methyl-4-[5(3)-ethyl-3(5)-pyrazolyl]pyridinium chloride

The compound, colorless crystals, melting point 250°–251° C., is prepared from the reaction of 4-[5(3)-ethyl-3(5)-pyrazolyl]pyridine and methyl chloride as described in Example 13, except that the reaction is carried out for 18 hours in a bomb at 90° C. with excess methyl chloride as solvent.

EXAMPLE 21

Preparation of 1-isopropyl-4-[5(3)-methyl-3(5)-pyrazolyl]pyridinium chloride

The compound, colorless crystals, melting point 242°–243° C., is prepared from 4-[5(3)-methyl-3(5)-pyrazolyl]pyridine and isopropyl chloride as described in Example 13, except that the reaction is carried out in a bomb for 18 hours at 80° C. with excess isopropyl chloride as solvent.

EXAMPLE 22

Preparation of 1-isopropyl-4-[5(3)-methyl-3(5)-pyrazolyl]pyridinium bromide

The above compound, colorless crystals, melting point 217°–218° C., is prepared from 4-[5(3)-methyl-3(5)-pyrazolyl]pyridine and isopropyl bromide following the procedure of Example 13, except that the reaction is carried out for 42 hours in a bomb at 160° C. with excess isopropyl bromide as solvent.

EXAMPLE 23

Preparation of 1-isobutyl-4-[5(3)-methyl-3(5)-pyrazolyl]pyridinium bromide

The compound, colorless crystals, melting point 235°–236° C., is prepared from 4-[5(3)-methyl-3(5)-pyrazolyl]pyridine and isobutyl bromide as described in Example 13, except that the reaction is carried out for 18 hours under reflux in n-butyl alcohol.

EXAMPLE 24

Preparation of 1-methyl-4-[5(3)-methyl-3(5)-pyrazolyl]pyridinium chloride

The compound, colorless crystals, melting point 251°–252° C., is prepared from 4-[5(3)-methyl-3(5)-pyrazolyl]pyridine and methyl chloride as described in Example 13, except that the reaction is carried out for 18 hours in a bomb at 90° C. with excess methyl chloride as solvent.

EXAMPLE 25

Preparation of 1-methyl-4-[3(5)-pyrazolyl]pyridinium chloride

The compound, colorless crystals, melting point 232°–233° C., is prepared from 4-[3(5)-pyrazolyl]pyridine and methyl chloride as described in Example 13, except that the reaction is carried out for 18 hours in a bomb at 90° C. with excess methyl chloride as solvent.

EXAMPLE 26

Preparation of 1-n-butyl-4-[5(3)-methyl-3(5)-pyrazolyl]pyridinium chloride

The above compound, colorless crystals, melting point 195°–196° C., is prepared from 4-[5(3)-methyl-3(5)-pyrazolyl]pyridine and n-butyl chloride using the procedure described in Example 13, except that the reaction is carried out for 18 hours under reflux with excess n-butyl chloride as solvent.

EXAMPLE 27

Preparation of 1-allyl-4-[5(3)-methyl-3(5)-pyrazolyl]pyridinium chloride

The compound, colorless crystals, melting point 243°–244° C., is prepared from 4-[5(3)-methyl-3(5)-pyrazolyl]pyridine and allyl chloride as described in Example 13, except that the reaction is carried out for 18 hours under reflux in methanol.

EXAMPLE 28

Preparation of 1-methyl-4-[5(3)-cyclopropyl-3(5)-pyrazolyl]pyridinium chloride

This compound, colorless crystals, melting point 259°–261° C., is prepared from 4-[5(3)-cyclopropyl-3(5)-pyrazolyl]pyridine and methyl chloride as described in Example 13, except that the reaction is carried out for 18 hours in a bomb at 90° C. with excess methyl chloride as solvent.

EXAMPLE 29

Preparation of 1-methyl-4-[4-methyl-3(5)-pyrazolyl]pyridinium iodide

The compound, colorless crystals, melting point 213°–214° C., is prepared from 4-[4-methyl-3(5)-pyrazolyl]pyridine and methyl iodide following the procedure described in Example 13, except that the reaction is carried out for 2 hours under reflux in methanol.

EXAMPLE 30

Preparation of 1,3-dimethyl-4-[5(3)-methyl-3(5)-pyrazolyl]pyridinium chloride

The above compound, colorless crystals, melting point 263°–265° C., is prepared from 3-methyl-4-[5(3)-methyl-3(5)-pyrazolyl]pyridine and methyl chloride as described in Example 13, except that the reaction is carried out for 20 hours in a bomb at 90° C. with excess methyl chloride as solvent.

EXAMPLE 31

Preparation of 1-methylallyl-4-[5(3)-methyl-3(5)-pyrazolyl]pyridinium chloride

The compound, colorless crystals, melting point 229°–230° C., is prepared from 4-[5(3)-methyl-3(5)-pyrazolyl]pyridine and methylallyl chloride following the procedure as described in Example 13, except that the reaction is carried out for 18 hours under reflux with excess methylallyl chloride as solvent.

EXAMPLE 32

Preparation of 1-cinnamyl-4-[5(3)-methyl-3(5)-pyrazolyl]pyridinium chloride

This compound, colorless crystals, melting point 207°–208° C., is prepared by reacting 4-[5(3)-methyl-3(5)-pyrazolyl]pyridine and cinnamyl chloride and using the procedure as described in Example 13, except that the reaction is carried out for 18 hours under reflux in ethanol.

EXAMPLE 33

Preparation of 1-(3-methyl-2-buten-1-yl)-4-[5(3)-methyl-3(5)-pyrazolyl]pyridinium chloride

The compound, colorless crystals, melting point 194°–195° C., is prepared from 4-[5(3)-methyl-3(5)-pyrazolyl]pyridine and 3-methyl-2-buten-1-yl chloride as described in Example 13, except that the reaction is carried out for 18 hours under reflux in ethanol.

9

yl]pyridine and 1-chloro-3-methyl-2-butene as described in Example 13, except that the reaction is carried out for 4 hours under reflux in n-propyl alcohol.

EXAMPLE 34

Preparation of 1-(2-buten-1-yl)-4-[5(3)-methyl-3(5)-pyrazolyl]pyridinium chloride

The above compound, colorless crystals, melting point 162°-163° C., is prepared by reacting 4-[5(3)-methyl-3(5)-pyrazolyl]pyridine and 1-chloro-2-butene using the procedure described in Example 13, except that the reaction is carried out for 18 hours under reflux in n-propyl alcohol.

EXAMPLE 35

Preparation of 1-(2-methoxyethyl)-4-[5(3)-methyl-3(5)-pyrazolyl]pyridinium chloride

The compound, colorless crystals, melting point 209°-210° C., is prepared from 4-[5(3)-methyl-3(5)-pyrazolyl]pyridine and 1-chloro-2-methoxyethane as described in Example 13, except that the reaction is carried out for 18 hours under reflux in n-propyl alcohol.

EXAMPLE 36

Preparation of 1-cyclopropylmethyl-4-[5(3)-methyl-3(5)-pyrazolyl]pyridinium bromide

The above compound, colorless crystals, melting point 220°-221° C., is prepared from 4-[5(3)-methyl-3(5)-pyrazolyl]pyridine and cyclopropylmethyl bromide as described in Example 13, except that the reaction is carried out for 18 hours at 90° C. in toluene.

EXAMPLE 37

Hard gelatin capsules

	Gm.
1 - methyl-4-[5(3)-ethyl-3(5)-pyrazolyl]pyridinium chloride	100
Cornstarch	75
Magnesium stearate, powder	25
Talc	25

The finely powdered ingredients are mixed thoroughly and then encapsulated in 1000 two-piece hard gelatin capsules each containing 100 mgs. of 1-methyl-4-[5(3)-ethyl-3(5)-pyrazolyl]pyridinium chloride.

EXAMPLE 38

Soft gelatin capsules

One piece soft gelatin capsules for oral use each containing 150 mgs. of 1-methyl-4-[5(3)-ethyl-3(5)-pyrazolyl]pyridinium iodide are prepared by first dispersing the compound in sufficient corn oil to render the material capsulatable and then encapsulating in the usual manner.

EXAMPLE 39

Tablets

1000 tablets each containing 100 mgs. of 1-methyl-4-[5(3)-methyl-3(5)-pyrazolyl]pyridinium chloride are prepared from the following ingredients:

	Gm.
1 - methyl - 4 - [5(3) - methyl - 3(5) - pyrazolyl] - pyridinium chloride	100
Lactose	50
Starch	50
Calcium stearate	10
Talc	10

The finely powdered ingredients are mixed thoroughly and then tableted by a slugging procedure.

EXAMPLE 40

Hard gelatin capsules

Five thousand two-piece hard gelatin capsules, each containing 200 mg. of 1-n-butyl-4-[5(3)-methyl-3(5)-

75

10

pyrazolyl]pyridinium bromide are prepared from the following ingredients:

	Gm.
1 - n - butyl - 4 - [5(3) - methyl - 3(5) - pyrazolyl] - pyridinium bromide	1000
Lactose	1500
Magnesium stearate	500
Talc	500

The finely powdered ingredients are mixed thoroughly and then encapsulated.

We claim:

1. A therapeutic composition for oral administration useful for the control of hyperglycemia in warm-blooded animals comprising a pyrazolylpyridinium salt of the formula:

wherein R is selected from the group consisting of hydrogen, lower alkyl and cyclopropyl; R₁ and R₂ are selected from the group consisting of hydrogen and lower alkyl; R₂ is selected from the group consisting of lower alkyl, lower alkenyl, cinnamyl, cyclopropylmethyl and lower alkoxy-(lower) alkyl; X is a pharmaceutically acceptable anion and a solid edible carrier.

2. A therapeutic composition in accordance with claim 1 wherein the pyrazolylpyridinium salt is 1-methyl-4-[5(3)-ethyl-3(5)-pyrazolyl]pyridinium chloride.

3. A therapeutic composition in accordance with claim 1 wherein the pyrazolylpyridinium salt is 1-methyl-4-[5(3)-ethyl-3(5)-pyrazolyl]pyridinium iodide.

4. A therapeutic composition in accordance with claim 1 wherein the pyrazolylpyridinium salt is 1-methyl-4-[5(3)-methyl-3(5)-pyrazolyl]pyridinium chloride.

5. A therapeutic composition in accordance with claim 1 wherein the pyrazolylpyridinium salt is 1-n-butyl-4-[5(3)-methyl-3(5)-pyrazolyl]pyridinium bromide.

6. A therapeutic composition in accordance with claim 1 wherein the pyrazolylpyridinium salt is 1-n-butyl-4-[5(3)-methyl-3(5)-pyrazolyl]pyridinium chloride.

7. A therapeutic composition in accordance with claim 1 wherein the pyrazolylpyridinium salt is 1-methyl-4-[5(3)-pyrazolyl]pyridinium chloride.

8. A therapeutic composition in accordance with claim 1 wherein the pyrazolylpyridinium salt is 1,3-dimethyl-4-[5(3)-methyl-3(5)-pyrazolyl]pyridinium chloride.

9. A therapeutic composition in accordance with claim 1 wherein the pyrazolylpyridinium salt is 1-(3-methyl-2-butene-1-yl)-4-[5(3)-methyl - 3(5) - pyrazolyl]pyridinium chloride.

10. A therapeutic composition in accordance with claim 1 wherein the pyrazolylpyridinium salt is 1-(2-buten - 1 - yl) - 4 - [5(3) - methyl - 3(5) - pyrazolyl]pyridinium chloride.

11. The method of inducing hypoglycemia which comprises administering orally to a warm-blooded animal in whom a hypoglycemic effect is desired an amount sufficient to produce hypoglycemia of a pyrazolylpyridinium salt of the formula:

wherein R is selected from the group consisting of hydrogen, lower alkyl and cyclopropyl; R₁ and R₃ are selected from the group consisting of hydrogen and lower alkyl; R₂ is selected from the group consisting of lower alkyl, lower alkenyl, cinnamyl, cyclopropylmethyl and lower alkoxy-(lower) alkyl; and X is a pharmaceutically acceptable anion.

12. The method of inducing hypoglycemia which comprises administering orally to a warm-blooded animal in whom a hypoglycemic effect is desired a sufficient amount of 1 - methyl - 4 - [5(3)-ethyl-3(5)-pyrazolyl]pyridinium chloride.

13. The method of inducing hypoglycemia which comprises administering orally to a warm-blooded animal in whom a hypoglycemic effect is desired a sufficient amount of 1 - methyl - 4 - [5(3) - ethyl - 3(5) - pyrazolyl]pyridinium iodide.

14. The method of inducing hypoglycemia which comprises administering orally to a warm-blooded animal in whom a hypoglycemic effect is desired a sufficient amount of 1 - methyl - 4 - [5(3) - methyl - 3(5) - pyrazolyl]pyridinium chloride.

15. The method of inducing hypoglycemia which comprises administering orally to a warm-blooded animal in whom a hypoglycemic effect is desired a sufficient amount of 1 - n - butyl - 4 - [5(3) - methyl - 3(5) - pyrazolyl]pyridinium bromide.

16. The method of inducing hypoglycemia which comprises administering orally to a warm-blooded animal in whom a hypoglycemic effect is desired a sufficient amount of 1 - n - butyl - 4 - [5(3) - methyl - 3(5) - pyrazolyl]pyridinium chloride.

17. The method of inducing hypoglycemia which comprises administering orally to a warm-blooded animal in

whom a hypoglycemic effect is desired a sufficient amount of 1 - methyl - 4 - [3(5) - pyrazolyl]pyridinium chloride.

18. The method of inducing hypoglycemia which comprises administering orally to a warm-blooded animal in whom a hypoglycemic effect is desired a sufficient amount of 1,3 - dimethyl - 4 - [5(3) - methyl - 3(5) - pyrazolyl]pyridinium chloride.

19. The method of inducing hypoglycemia which comprises administering orally to a warm-blooded animal in whom a hypoglycemic effect is desired a sufficient amount of 1 - (3 - methyl - 2 - buten - 1 - yl) - 4 - [5(3) - methyl-3(5)-pyrazolyl]-pyridinium chloride.

20. The method of inducing hypoglycemia which comprises administering orally to a warm-blooded animal in whom a hypoglycemic effect is desired a sufficient amount of 1 - (2 - buten - 1 - yl) - 4 - [5(3) - methyl - 3(5) - pyrazolyl]pyridinium chloride.

UNITED STATES PATENT OFFICE
CERTIFICATE OF CORRECTION

Patent No. 3,341,413

September 12, 1967

Edward Charles Tocus et al.

It is hereby certified that error appears in the above numbered patent requiring correction and that the said Letters Patent should read as corrected below.

Columns 3 and 4, in the TABLE, second column, line 18 thereof, for "270" read -- 250 --; same TABLE, third column, line 18 thereof, for "88" read -- 66 --; same TABLE, sixth column, line 12 thereof, for "35+8" read -- 36+8 --; column 7, line 30, for "pyraxol-", in italics, read -- pyrazol- --, in italics; column 10, lines 16 to 21, for that portion of the formula reading

$$\begin{array}{ccc} & | & \\ & R_2 & \\ & | & \\ & \text{read} & \\ & | & \\ & R_3 & \end{array}$$

Signed and sealed this 1st day of October 1968.
